UNITED STATES PATENT OFFICE.

NORMAN SINCLAIR McNAB, OF CAULFIELD, VICTORIA, AUSTRALIA.

COIN-FREEING MECHANISM FOR AUTOMATIC VENDING AND OTHER MACHINES.

1,179,124.

Specification of Letters Patent. Patented Apr. 11, 1916.

Application filed June 17, 1914. Serial No. 845,721.

To all whom it may concern:

Be it known that I, NORMAN SINCLAIR McNAB, a subject of the King of Great Britain, residing at Waiora Road, Caulfield, in the State of Victoria, Commonwealth of Australia, have invented certain new and useful Improvements in Coin-Freeing Mechanism for Automatic Vending and other Machines, of which the following is a specification.

This invention consists of improvements in coin freeing mechanism for automatic vending machines, and the principal object is to insure the ejection of coins of wrong size and weight and to prevent the manually or power operated lever of the machine from being operated until a proper coin is fed into the machine.

The improvements shown in the drawings are applied to a stamp vending machine by way of exemplification.

Figure 1 is a sectional plan of a manually operated stamp vending machine with the improvements attached. Figs. 2 and 3 are respectively a vertical section on lines 11—11 and 111—111 of Fig. 1. Figs. 4 and 5 are enlarged details of parts shown in Figs. 1—3. Fig. 6 is a sectional view corresponding to the lower parts of Figs. 2 and 3 illustrating a power means of operating the machine automatically.

Referring to Figs. 1—5 the coin C is inserted at slot (1) formed in the casing C and as it abuts against curved shoulder 2 inside said casing it turns by gravity on the ridge 3 of plate 3^a until it reaches a "sliding angle" when it moves or slides under plate 4 on to the receiving tray or plate 5 of a spring or weight balanced lever 6, which, if the coin is heavier than the weight the balance is adjusted for, moves and the coin slides off the tray into chute 7 through opening 8 and from thence into the delivery mouth 9 of the machine. The plate 4 prevents the coin from passing over the balance tray 5 until it ceases rocking thereon.

If the coin is lighter than the weight balance lever 6 is adjusted for, the coin slides over same on to plate 10 which is tilted or obliquely arranged forwardly and laterally inclined as shown in Fig. 4. This plate 10 is provided with slot 11 and a projection or ridge 10^a on its lower side whereby coins of a less diameter than the proper size fall through the slot down the chute 7 and from thence to the delivery mouth or receptacle 9 of the machine.

A coin passing over the slot 11 moves by gravity against the ridge on the lower side and is delivered onto a plate or receiving tray 12 of a spring balanced lever 13 the upward movement of which is controlled by a stop 13^a. The tray 12 is pivotally balanced as at 14 upon the spring controlled pivoted lever 13 and the movement of the tray is regulated by stops 15, 16 thereon. The weight of the coin causes the tray, which is normally, almost horizontal, to tilt sufficiently to allow the coin to slide off and, should the coin be lighter than the weight the balance lever 13 is adjusted for, the coin slides on to plate 17 of the chute 7 and from thence to the delivery mouth 9 of the machine. The tray 12 also has a curved pocket 18 to reduce the rocking or vibration of the coin. If the coin is of the required weight it moves the balance lever 13 and the coin slides off into the tube 19 and dropping on to arm or plate 20 of lever 30 it moves same to disengage the spring controlled hook or pawl 21 from coin tray 22 on lever 23 by means of projection 30^b.

The hook 21 and arm 20 above described are pivoted on a common fulcrum 30^a so as to permit the hook moving independently of the arm in the action of the resetting of coin tray 22. The hook is controlled by spring 21^a and the arm 20 suitably counterbalanced.

The weight of the coin on falling upon the tray will lower the lever 23, and, in doing so move connecting rod 24 (Fig. 3) and the pawl 25 to release stop 26 and allow the crank disk 27 connected indirectly with the main operating lever 31 of the vending machine to be turned by knob 28 to actuate the mechanism of said machine. The knob 28 is not connected rigidly to the crank disk but rotates same through the agency of friction plates 32, 33 and spring 34 as in Fig. 5. The crank disk has ratchet teeth 35 around its periphery and is prevented from backward rotation by staggered pawls 36, 37 engaging therein. The crank disk 27 reciprocates a rod 38 connected to a slide rod 39 which in turn actuates the aforementioned stamp mechanism operating lever 31 by link 40. The reciprocating movement of this stamp mechanism operating lever feeds the stamp S forward and detaches same and the stamp then drops through tube 41 into the delivery mouth of the machine.

A grooved knife edge 42 is formed on

plate 10 to cut any threads which may be attached to coins for the purpose of tampering with the machine.

To insure that the coin tray 22 is reset after each operation, a chain 43 or other suitable telescopic joint is connected between the balance lever 23 and the stamp mechanism operating lever 31 in a way that the movement of the main stamp mechanism lever 31 will reset the coin tray lever 22 in engagement with hook 21 before it detaches the stamp just purchased.

The "empty" dial E (Figs. 2 and 3) is connected to a balanced lever 45 pivoted as at 44 and held out of sight by pin 45^a lying normally under and against the stamp band S which passes under a curved plate 50 attached to frame so that when the end of the band clears the edge of plate 50 the lever 45 moves by gravity, as indicated by arrow, and the dial E marked "Empty" appears at the aperture 46 in front of the machine as in Fig. 2. At the same time a projection 47 on the lever 45 is moved into the plane of movement of tray 12 (Fig. 2) which is thus prevented from lowering the lever 13 as indicated by dotted lines so that any coins now delivered on to tray 12 fall on to plate 17 and from thence to the delivery mouth 9 of the machine.

Instead of a manually turned knob 28 to rotate the crank disk 27 and so reciprocate the main operating lever 31 of the vending machine said lever 31 may be reciprocated by a crank disk 51 through rod 65 (Fig. 6). The disk is rotated by a worm 52 on the spindle 62 of an electro-motor 53 the circuit of which is made by a contact 54 on a spring controlled arm 55 projecting from fulcrum 56 of the coin tray lever 23 and a vessel 57 containing mercury or other suitable contact. A projection 64 on the arm 55 is adapted to engage a spring controlled pawl 63 to hold down the spring controlled contact 54 and maintain the circuit while the mechanism is in operation. Stud 59 on the crank disk 51 engages projection 60 on tray lever 23 and moving same resets the latter; the stud also moves the pawl 63 and releases the projection 64 and in consequence the spring controlled arm 55 which breaks the circuit and stops the motor. A knob 61 may be attached to the worm or preferably to the motor spindle 62 so that the machine may be operated manually as well when the machine is unlocked.

I claim:

1. In coin freeing mechanism for auto-

matic vending and other machines, the combination of a spring-controlled lever, a coin-receiving tray pivotally balanced on said lever, a second lever having means adapted to move into the plane of movement of said tray to prevent the downward movement of said lever, and an indicator attached to said second lever.

2. In an automatic vending or other machine, of a spring-controlled lever, a coin-receiving tray mounted on said lever and movable independently thereof for ejecting a coin of insufficient weight from the machine, said lever being movable with said tray to deposit a coin within the machine when a coin of sufficient weight is received on the tray, and means to prevent the actuation of said lever.

3. In a coin-freeing mechanism for automatic vending and other machines, a spring-controlled lever, a coin-receiving tray pivotally balanced on said lever, and means movable into the plane of movement of said tray when the machine is empty and to prevent said spring-controlled lever from being actuated when a coin is received on said tray.

4. In an automatic vending mechanism a spring-controlled lever, a coin-receiving tray mounted on said lever and tilttable independently of the latter to eject a coin of insufficient weight from the machine, said lever being actuated with said tray when a coin of proper weight is received by the latter to deposit said coin in the machine, and means operative when the machine is empty to prevent the actuation of said lever.

5. In combination with a vending mechanism and coin-controlled locking means therefor, of a spring-controlled lever, a coin-receiving tray mounted on said lever and tilttable independently of the latter to eject a coin of insufficient weight, said lever being actuated with said tray when a coin of proper weight is received by said tray to deliver said coin to said locking means to unlock the latter, and a second lever movable into the path of said tray when the machine is empty to prevent movement of said first-named lever.

In testimony whereof I have hereunto set my hand in presence of two subscribing witnesses.

NORMAN SINCLAIR McNAB.
